UNITED STATES PATENT OFFICE.

GLADYS C. KANE, OF WASHINGTON, DISTRICT OF COLUMBIA.

DESIGN FOR A COMBINATION FLOWER-HOLDER AND DRESS-PROTECTOR.

51,305.

Specification for Design. Patented Sept. 25, 1917.

Application filed April 2, 1917. Serial No. 159,350. Term of patent 14 years

To all whom it may concern:

Be it known that I, GLADYS C. KANE, a citizen of the United States, residing at Washington, in the District of Columbia, have invented a new, original, and ornamental Design for a Combination Flower-Holder and Dress-Protector, of which the following is a specification, reference being had to the accompanying drawing, forming a part thereof.

In the drawing:—

Fig. 2 is a similar view looking at the rear of the protector:—and

Figs. 3 and 4 are top plan views of Figs. 1 and 2 respectively.

I claim:

The ornamental design for a combination flower holder and dress protector, as shown.

GLADYS C. KANE.
